(57) **CLAIM**

The ornamental design for a smart fish tank, as shown and described.

DESCRIPTION

FIG. 1 is a front view of a smart fish tank showing my new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof; and,

FIG. 7 is a perspective view thereof.

The broken lines in the drawings depict portions of the smart fish tank and form no part of the claimed design.
